United States Patent Office

Des. 208,870
Patented Oct. 10, 1967

208,870

CLOCK

Robert E. Murray, 13962 Holt Ave.,
Santa Ana, Calif. 92705

Filed July 5, 1966, Ser. No. 2,920

Term of patent 3½ years

(Cl. D42—7)

FIG.1

FIG.2

FIG.3

FIG.4

FIGURE 1 is a front elevational view of a clock showing my new design;

FIGURE 2 is a side elevational view thereof;

FIGURE 3 is a rear elevational view of the clock; and

FIGURE 4 is a top plan view thereof.

The side opposite that seen in FIGURE 2 is substantially a mirror image thereof.

I claim:

The ornamental design for a clock, as shown and described.
